A. A. KRAEUTER

GOLF CLUB

Filed Jan. 18, 1924

UNITED STATES PATENT OFFICE.

ARTHUR A. KRAEUTER, OF SOUTH ORANGE, NEW JERSEY, ASSIGNOR TO KROYDON CO.,
A CORPORATION OF NEW JERSEY.

GOLF CLUB.

Application filed January 18, 1924. Serial No. 686,972.

To all whom it may concern:

Be it known that I, ARTHUR A. KRAEUTER, a citizen of the United States, residing at South Orange, in the county of Essex and State of New Jersey, have invented certain new and useful Improvements in Golf Clubs; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in golf-clubs; and, the present invention has reference, more particularly to a novel construction of handle for golf-clubs and ferrule therefor, with a view of 20 providing the leather-bound handle-portion of the golf-club with a means, in the form of a neat and ornamental end-ferrule, which with constant use of the golf-club, will prevent the usual unsightly unravelling of 25 the leather or other material employed as a binding.

The present invention, therefore, has for its principal object to provide a golf-club of the general character hereinafter set forth, the handle-portion of the club being bound spirally with leather or similar material, and the end of the handle-portion being topped off with means, preferably in the form of an ornamental ferrule to prevent unravelling of the leather or other material employed to produce the handle-portion of the golf-club.

The invention has for its further object to provide in connection with the end-portion of the leather-bound handle-portion of a golf-club, a ferrule having upon its inside a taper, which as the ferrule is screwed upon the end of the handle jams down upon the leather and firmly pinches it, so 45 that any possibility of the leather unravelling at the end of the handle-portion is absolutely overcome.

Other objects of the present invention not at this time more particularly enumerated 50 will be clearly understood from the following detailed description of the present invention.

With the various objects of the present invention in view, the said invention consists, 55 primarily, in the production of a golf-club

having a leather-bound handle-portion provided with means to prevent unravelling of the leather; and, the invention consists furthermore, in the general arrangements and combinations of the various devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:—

Figure 1 is a view of a golf-club provided with a leather-bound handle-portion and a ferrule therefor, all arranged and made according to the principles of the present invention; Figure 2 is a view, on an enlarged scale, showing in elevation, a fragmentary portion of the screw-threaded end of the leather-bound handle-portion of the golf-club, with the ferrule in position upon said screw-threaded end, the ferrule, however, being shown in vertical section; and Figure 3 is an end view of the parts represented in said Figure 2.

Figure 4 is a view similar to Figure 2, in which the arrangement of the screw-threads of the end of the leather-bound handle-portion and of the ferrule are arranged in a reverse manner from that shown in said Figure 2; and Figure 5 is an end view of a slightly modified form of ferrule.

Figure 6 is a detail sectional representation, on a still larger scale, of fragmentary parts of the screw-threaded end of the handle-portion of the golf-club and of the ferrule, said view illustrating the metal ferrule provided with a sharp thread, and the wooden screw-threaded part of the handle-portion with a blunt thread.

Similar characters of reference are employed in all of the said above described views, to indicate corresponding parts.

Referring now to the several figures of the drawings, the reference-character 1 indicates the usual stick of a golf-club, provided with a suitably formed off-set portion, as 2, see Figure 2, which is made with a tapered part 3 from which extends a reduced portion 4 which is provided with an arrangement of screw-threads 5. These screw-threads being made in the wood must of necessity be blunt, substantially as indicated

at 6 in Figures 2 and 6 of the drawings. In the arrangement of the parts, as indicated in Figure 2 of the drawings, the screw-threads are left-hand threads, while 5 in the construction represented in Figure 4 of the drawings, which in all respects is similar to the construction shown in said Figure 2, the screw-threads are right-hand threads.

10 The usual spirally wound binding of leather, or similar suitable material, is indicated by the reference-character 7, the said binding as will be evident from an inspection of Figures 2 and 4 of the drawings, being wound and terminating about the offset portion 2 of the stick 1, as at 8, the layers of the material 7 being secured in the usual manner by means of cement, glue, or the like. In order to prevent loosening or unravelling of the terminating portions 8 of the binding 7, as is so common in the construction of the handle-portions of golf-clubs, as at present made, I employ a metal ferrule or cap, of the construction to be presently more fully described, the said ferrule or cap serving a two-fold purpose:—one as an ornament for the end of the golf-club, and the other to provide a retaining means which prevents any possibility of the terminating portion 8 of the binding unravelling or fraying, as will be evident.

The construction of the ferrule shown more particularly in Figures 2, 3 and 4 of the drawings, consists essentially of a tubular body 9, the outer surface-portion of which may be suitably convexed, or otherwise shaped. Within its tubular portion, the said body 9 is tapered, as at 10 and 11, corresponding to the tapered surfaces of the parts 2 and 3 of the stick 1. Above the tapered part 11, the said ferrule is internally screw-threaded, as at 12, the said screw-threads corresponding to the arrangement of left or right-hand screw-threads 5, shown in said Figures 2 and 4 of the drawings, but the screw-threads 12 being made sharp, so that when the ferrule is screwed upon the reduced portion 4, the sharp screw-threads 12 will bite into the wood, whereby a permanent and positive assemblage of the ferrule with relation to the end of the golf-club will be the result. Furthermore, the taper inside of the ferrule pinches the terminal end-portion of the leather binding, thereby 50 jamming the leather, and producing a very tight and fixed position of the ferrule upon the handle-portion of the golf-club. If desired the internally screw-threaded portion of the ferrule may be left open, as at 13, through which the end-surface 14 of the stick, after being properly finished off, is exposed, as shown in said Figures 2 and 4 of the drawings.

This, however, is not essential, and in lieu of the ferrule I may use a cap 15 which is provided with a closed end 16, as will be evident from an inspection of Figure 5 of the drawings. In all other respects, the inner portion of the said cap 15 is internally tapered and internally screw-threaded in the same manner as the ferrule shown in said Figures 2, 3 and 4.

Having in the foregoing described the present invention, what I claim is:—

1. A golf-club comprising a stick formed with tapered portions, a leather binding wound about a portion of said stick and about one of said tapered portions of the stick, and a ferrule mounted upon the end-portion of said stick, said ferrule having internally tapered portions corresponding to the tapered portions of the stick, all arranged to jam and pinch the end of the leather binding to prevent fraying or unravelling of the binding. 85

2. A golf-club comprising a stick formed with tapered portions, and a screw-threaded end-member extending from one of said tapered portions, a leather binding wound about a portion of said stick and about the other tapered portion of the stick, and a ferrule mounted upon the end-portion of the stick, said ferrule having an internally screw-threaded part screwed upon the screw-threaded end-member of the stick, and said ferrule having internally tapered portions corresponding to the tapered portions of the stick, all arranged to jam and pinch the end of the leather binding to prevent fraying or unravelling of the binding. 95

3. A golf-club comprising a stick of wood formed with tapered portions, and a screw-threaded end-member extending from one of said tapered portions, the screw-threads of said end-member being blunt, a leather binding wound about a portion of said stick and about the other tapered portion of the stick, and a ferrule mounted upon the end-portion of the stick, said ferrule having an internally screw-threaded part composed of sharp screw-threads, screwed upon the screw-threaded end-member with said sharp threads biting into said end-member, and said ferrule having internally tapered portions corresponding to the tapered portions of the stick, all arranged to jam and pinch the end of the leather binding to prevent fraying or unravelling of the binding. 100

In testimony, that I claim the invention set forth above I have hereunto set my hand this January, day of 11th, 1924. 120

ARTHUR A. KRAEUTER.
